UNITED STATES PATENT OFFICE

HENRY R. LOVELL, OF GREENVILLE, PENNSYLVANIA

DESIGN FOR A DOORCHECK

Application filed May 25, 1932. Serial No. 43,898. Term of patent 14 years.

To all whom it may concern:

Be it known that I, HENRY R. LOVELL, a citizen of the United States of America, residing at Greenville, in the county of Mercer and State of Pennsylvania, have invented a new, original, and ornamental Design for a Door Check, of which the following is a specification, reference being had to the accompanying drawing, forming a part thereof.

I claim:—

The ornamental design for a door check as shown.

HENRY R. LOVELL.
